[57] CLAIM

The ornamental design for an inhaler mask, as shown and described.

DESCRIPTION

FIG. 1 is a left front perspective view of a first embodiment of our design;

FIG. 2 is a top plan view thereof;

FIG. 3 is a front elevation view thereof;

FIG. 4 is a right side elevation view thereof, the left side elevation view being a mirror image thereof;

FIG. 5 is a bottom plan view thereof;

FIG. 6 is a rear elevation view thereof; and

FIG. 7 is a sectional view thereof, taken along line 7—7 of FIG. 3;

FIG. 8 is a front left side perspective view of a second embodiment of our design;

FIG. 9 is a top plan view thereof;

FIG. 10 is a front elevation view thereof;

FIG. 11 is a right side elevation view thereof, the left side elevation view being a mirror image thereof;

FIG. 12 is a bottom plan view thereof;

FIG. 13 is a rear elevation view thereof; and

FIG. 14 is a section elevation view, taken along line 14—14 in FIG. 10;

FIG. 15 is a front perspective view of a third embodiment of our design;

FIG. 16 is a top plan view thereof;

FIG. 17 is a front elevation view thereof;

FIG. 18 is a right side elevation view thereof, the left side elevation view being a mirror image thereof;

FIG. 19 is a bottom plan view thereof;

FIG. 20 is a rear elevation view thereof; and,

FIG. 21 is a section elevation view, taken along line 21—21 of FIG. 17.
